UNITED STATES PATENT OFFICE.

HERMAN ZENAS TILLOTSON, OF WASHINGTON, DISTRICT OF COLUMBIA.

SUPPORTER.

Application filed October 5, 1925. Serial No. 60,605.

To all whom it may concern:

Be it known that I, HERMAN ZENAS TILLOTSON, a citizen of the United States, residing in the city of Washington, District of Columbia, have invented certain new and useful Improvements in Supporters, of which the following is a specification.

This invention relates to supporters, more particularly to the type of ornamented 10 rolled stocking supporter, and has for its object to provide, in a manner as herein-after set forth, a supporter of the class referred to, capable of being conveniently applied to the rolled upper portion of a stocking, when on the leg of the wearer, for the purpose of maintaining the stocking in set 15 position to prevent it from falling down when worn, and further providing means for displaying an ornament at the top of the stocking without directly attaching the ornament to the stocking.

A further object of the invention is to provide, in a manner as herein-after set forth, a rolled top stocking supporter capable of displaying a decorating ornament 25 at the top of the stocking without attachment directly to the latter and without imparting a bulky or unsightly effect to the stocking top.

30 A further object of the invention is to provide, in a manner as herein-after set forth, a rolled top stocking supporter providing means for maintaining the rolled portion of the stocking in position and whereby said rolled portion will conceal a 35 garter when worn.

A further object of the invention is to provide, in a manner as herein-after set forth, a rolled top stocking supporter for 40 efficiently supporting the stocking in set position, when worn, especially when the stocking is wet and worn at bathing beaches, and further to provide a device of the class referred to, which is not injurious in any 45 manner to the stocking when applied to the latter when employed to perform its supporting function with respect to the stocking.

A further object of the invention is to 50 provide, in a manner as herein-after set forth, a stocking supporting device for use in connection with adult and children's stockings for the purpose of supporting them when worn in set position, and further to provide a supporting device for the 55 purpose referred to wherein any character

of ornament can be displayed without a garter being visible, and further to maintain the stocking in tightly rolled condition at the upper portion thereof when supporting the ornament.

Further objects of the invention are to provide, in a manner as herein-after set forth, a stocking supporter of the type referred to, which is simple in its construction 65 and arrangement, strong, durable, compact, ornamental in appearance, thoroughly efficient in its use, conveniently applied, and comparatively inexpensive to manufacture.

With the foregoing and other objects in view, the invention consists of the novel construction, combination and arrangement of parts, as herein-after more specifically described and illustrated in the accompanying drawings, wherein is shown an embodiment 75 of the invention, but it is to be understood that changes, variations and modifications can be resorted to which come within the scope of the claims hereunto appended.

In the drawings wherein like reference characters denote corresponding parts throughout the several views:—

Figure 1 is a perspective view of a leg provided with a rolled top stocking and showing the adaptation therewith of a supporter, in accordance with this invention.

Figure 2 is a side elevation of the supporter prior to the positioning of the same with respect to the rolled upper portion of the stocking.

Figure 3 is a side elevation of the supporter in securing position with respect to the rolled upper portion of the stocking.

Figure 4 is a fragmentary view in rear elevation of the supporter.

Figure 5 is a fragmentary view, in elevation, of the supporter and illustrating the garter element thereof.

Figure 6 is a side elevation of a modified form of supporter in securing position with respect to the rolled portion of the stocking.

Referring to Figures 1 to 5, 1 denotes the representation of the leg of a person having arranged thereon a stocking 2 formed with a rolled top 3, and arranged in securing position with respect to the top 3, for the purpose of maintaining the stocking 2 in set position, is a supporter in accordance with this invention and which is referred to generally by the reference character 4, and which has as a permanent part thereof an ornamenting element 5 positioned against

the outer wrap of the rolled portion 3 and concealing a part of a roll retaining or embracing member referred to generally by the reference character 6.

5 In the form shown in Figures 1 to 5, the supporter comprises an anchoring means in the form of a leg encircling element which is termed a garter 7, which when the supporter is applied, is interposed between the rolled portion 3 of the stocking 2 and the body of the stocking as illustrated in Figure 3. The garter 7 can be of any form desired, that is to say of the adjustable type or formed of a length of elastic 10 webbing, or non-adjustable, but as shown by way of example is illustrated as the adjustable type provided with buckles. It is to be understood, however, that the garter 7 can be constructed in any manner desired, 15 as well as formed from any desired material.

The retaining member 6 is slidably mounted at one end, on the garter 7 and is preferably of a length, when bent transversely 20 thereof, to embrace the roll 3 and be positioned between the body of the stocking and the leg 1. The retaining or embracing member 6 is such as to possess an inherent holding characteristic for the purpose 25 of maintaining the wraps of the rolled portion 3 tightly together when said member is in retaining or in embracing position with respect to the roll 3. The member 6 can be formed of any suitable means possessing the aforesaid characteristic and preferably the member 6 consists of a length of 30 non-elastic, bendable, light metallic material 7' and which is enclosed by a fabric casing 8. The upper end of the member 40 6 is bent upon itself, as at 9, to provide a loop 10 to permit of the mounting of said member 6 on the garter 7. The bent portion of the member 6 is secured to the body of the latter by a suitable stitching 45 11 for engagement with the fabric casing 8.

Secured to the member 6 and forming a permanent part of the supporter, is the ornament 5. The ornament 5 is secured to the outer face of the member 6 at a point between its transverse median and its upper end, and when the supporter is applied to the rolled top 3 of the stocking 2 the ornament 5 is positioned against the outer wrap of the roll 3 and conceals the member 6. 55 It is to be understood that any other style of ornament other than the ornament 5 can be connected to the member 6, such as a pendant, brooch, etc.

When the supporter is applied to the stocking 2, the garter 7 is interposed between the roll 3 and the body of the stocking 2, see Figure 3, and the retaining member bent around the outer face of the roll 3 and extended downwardly between the 65 stocking 2 and the leg 1. As the body por-

tion 7 of the member 6 is of non-elastic, light, bendable, metallic material, the roll 3 will be secured tightly together whereby it will be maintained in position and the stocking will be supported in set position so that it will not fall down when worn. The garter 7 assists in securing the stocking in set position.

In a great many instances, the rolled portion of the stocking acts as a means to support the stocking as long as the wraps of the roll are held tightly together, but the moment that the roll becomes loose, the stocking will fall and for the purpose of maintaining the roll in tight position to support the stocking and without the employment of a garter, the form of supporter shown in Figure 6 is employed. The form shown in Figure 6 consists of a retaining member 12 constructed of a body portion formed of a length of non-elastic, bendable, light, metallic material encased by a fabric casing and bent upon itself and secured together, as at 13. The bent portion 13 carries a headed stud 14. The member 12, at its upper end, is also bent upon itself and secured together as at 14' for connecting therewith a fastener member 15 which coacts with the headed stud 14 for anchoring the member 12 around the roll 3 to maintain the wraps thereof tightly together. The outer face of the member 12 has secured thereto an ornament 16 for the purpose of concealing said member 12 when the latter is in retaining position.

When the form of supporter shown in Figure 6 is employed, the member 12 is arranged against the outer face of the roll 3 and extends between the leg 1 and the stocking 2, and the fastener member 15 depends from the roll 3 and coacts with the stud 14 for coupling therewith the portion 17 of the stocking 2 to maintain the retaining member in position, and when the elements are arranged in the manner as stated, the supporter secures the rolled top stocking in set position.

It is thought the many advantages of a supporter, in accordance with this invention, for rolled top stockings, can be readily understood, and although the preferred embodiment of the invention is as illustrated and described, yet it is to be understood that changes in the details of construction can be had which will fall within the scope of the invention as claimed.

What I claim is:—

1. A device for the purpose set forth comprising a roll embracing element for the rolled portion of a stocking to prevent the unwinding of the roll and the falling of the stocking from set position and consisting of a strip of non-elastic, bendable material possessing a characteristic to maintain itself in embracing position with respect to said

rolled portion, and means for anchoring said element with respect to the leg of the wearer.

2. A stocking supporter for the purpose set forth comprising a garter adapted to be positioned between the rolled portion of the stocking and the body of the latter whereby said rolled portion will conceal the garter, and a retaining element formed of a narrow strip of non-elastic material connected at its upper end to said garter and bendable transversely to embrace and extend around the outer periphery of the rolled portion of the stocking to prevent the unwinding thereof and further in connection with the garter preventing the falling of the stocking when worn.

3. A stocking supporter for the purpose set forth comprising a garter adapted to be positioned between the rolled portion of the stocking and body of the latter whereby said rolled portion will conceal the garter, and a retaining element connected to the garter and embracing the rolled portion of the stocking to prevent the unwinding thereof and further in connection with the garter preventing the falling of the stocking when worn, said element having a shiftable connection with said garter to permit of the adjusting of the element on the garter.

30 4. A stocking supporter for the purpose set forth comprising a garter adapted to be positioned between the rolled portion of the stocking and the body of the latter whereby said rolled portion will conceal the garter, a retaining element formed from a strip of non-elastic, bendable material connected at one end to the garter and extending around the outer periphery of the rolled portion of the stocking to prevent the unwinding there-

of and further in connection with the garter 40 preventing the falling of the stocking when worn, and said strip of a length to extend into the stocking when in encircling position with respect to the rolled portion of the stocking.

45 5. A stocking supporter for the purpose set forth comprising a garter adapted to be positioned between the rolled portion of the stocking and the body of the latter whereby said rolled portion will conceal the garter, and a retaining element connected to the garter and embracing the rolled portion of the stocking to prevent the unwinding thereof and further in connection with the garter preventing the falling of the stocking when 50 worn, and said element of a length to extend into the stocking when in embracing position with respect to the rolled portion of the stocking, said element provided with means for shiftable connecting it with the 55 garter to provide for the adjusting thereof to various positions on the garter.

6. The combination with the rolled upper terminal portion of a stocking, of means to prevent the unwinding of said rolled portion 60 consisting of a flat strip of non-elastic metallic material bendable transversely on itself throughout its length to tightly engage and of appropriate length to embrace such rolled portion and possessing the characteristic to maintain itself in bent position when embracing said rolled portion to prevent the unwinding or loosening of the latter.

70 In testimony whereof I affix my signature 75 hereto.

HERMAN ZENAS TILLOTSON.
